1 Claim. (Cl. 139—190)

ABSTRACT OF THE DISCLOSURE

A beating up mechanism for weaving machines, wherein in the reciprocating movement of the lay and reed is caused by means of two sets of first and second cams forming a unit axially displaceable on a driven cam shaft for selective engagement with a pair of divergent arms secured to said lay and provided on their ends with respective rollers, so that the operation of said lay and reed may be altered.

This invention relates to an improved mechanism for actuating the reciprocal movement of the lay in weaving machines.

In looms provided with shuttles or other means for traversing the filling yarn, the lay reciprocates at intervals which are very short in relation to the entire weaving cycle. In looms using gripping means secured to a stem which goes into and out of the shed, the insertion of the weft constitutes an important part of the operating cycle of the machine. During said entire time, the lay remains generally behind said stem so as not to recede much behind the heddles which would increase the height of the shed, and not to increase the stroke of the element actuating the gripper. The dimensions of said element, the complex construction of the loom, and the inertia forces acting on the mechanism actuating said gripper, generally reduce the time during which the gripper is outside of the shed, to a minimum. It is during said brief time interval that the lay must be actuated.

The gripping means and its actuating mechanism have normally a much smaller cross-section than a shuttle; therefore, the motion of the lay can be considerably reduced in looms operating with grippers. The conventionally used lays are heavy and produce vibrations by their oscillating back and forth movements.

When such lay pushes the filling against the fell, it does not always operate in a constant plane. Gradually, a concave or convex longitudinal deformation may develop which causes the lay to strike more at its ends than in the center, or vice versa. Some types of fabrics do not require looms of large dimensions. In such looms, the movement of the lay must be not only fast but also short. Similarly, in looms which produce terry cloth, such as towels, the movements of the lay must be variable and adjustable, and especially in shuttleless looms, the stroke of the lay should be short.

It is, therefore, a principal object of the invention to provide an improved lay actuating mechanism which avoids the recited drawbacks.

Other objects and advantages will be apparent on consideration of the specification and claim.

The invention provides a lay which remains completely flat over the whole width of the fabric and ensures that in the case of variations in force of the blows such forces are absolutely constant, thereby producing a fabric of perfect appearance. In small looms with shuttle which must operate at high speeds, the recited results are obtained without any risk of deformation.

The lay according to the invention comprises an oscillating reed-carrying beam which is supported at two points

2

at its ends and has a continuous open or closed profile of triangular, angular, or any other cross-section suitable to increase the resistance against deformation and torsion; in this way, each stroke of the beam, which may be called lay beam, is exactly equal to the following, and the plane surface of the profile, when used in looms with shuttle, favors the free and guided passage of the shuttle.

The reed is attached to the upper part of the lay beam along its entire length, and two divergent arms are secured to the ends of the beam which arms carry at their ends rollers which are in contact with cams. One of said rollers rides on the periphery of a cam whose most protruding radial portion will cause the arm to oscillate and rise so as to displace the lay beam with the reed forwardly as the cam shaft rotates. The periphery of the other cam has a groove so arranged that, on continued rotation of the cam shaft, the roller of the second arm engages said groove and actuates the return movement of the reed. Therefore, due to the continuous rotation of the cam shaft, the lay beam makes an oscillating back and forth movement in uniform strokes each time it grasps the weft thread.

The cam shaft is driven from a drive shaft provided with a flywheel to prevent by its inertia fluctuations in the rocking movement of the lay beam.

When the rhythm of the movement of the lay should be varied in the beating-up motion, e.g., for the formation of loops or the like, the cam shaft is provided with at least two sets of such cams which are axially displaceable. Their peripheral dimensions are adapted to the different predetermined rocking paths of the lay. For the axial displacement of said cams, a fork may be provided which pushes a sleeve carrying the cams and which adjusts the required position of said sleeve by oscillating movement of said fork produced in suitable manner from the loom.

The present invention will be more clearly understood by reference to the accompanying drawings in which

FIG. 1 is a lateral elevation view of one embodiment of the invention showing the lay in retracted position for the passage of the weft thread;

FIG. 2 is a rear view of said lay, part cut away;

FIG. 3 is a view similar to FIG. 1 in the active position;

FIG. 4 is similar to FIG. 2 but showing means for varying the movement of the lay, and

FIG. 5 shows a detail of the mechanism.

Referring now first to FIGS. 1-3, a reed 1 is secured to the lay beam 2 by means of screws 3 (FIG. 2) whereby the lay beam 2 oscillates in a back and forth movement on shafts 4, 5 supported in bearings 6, 7. At the supporting shaft 5, there are secured two arms 8 and 9, which are provided with rollers 10 and 11. In neutral position, roller 10 rides on the periphery of cam 12, and roller 11 on that of cam 13, thus causing open vertical position of the lay 2 and, accordingly, of reed 1.

Said two cams 12 and 13, which latter is shown in FIG. 5, are rotated on shaft 14 which is driven over gears 15, 16 from a drive shaft 17 provided with a flywheel 18.

On rotation of shaft 17, the flywheel 18 also rotates and accumulates power which is transmitted through pinion 16 to the toothed wheel 15 driving the shaft 14 which in turn drives the two cams 12 and 13. Cam 12 has an eccentric portion 12' which raises the roller 10 of the arm 8 so as to oscillate the supporting shaft 5 of the lay beam 2 with the reed 1; thereby, the filling 19 is pushed against the line of cloth formation 20 (FIG. 3). Continuing rotation of shaft 14 forces the other cam 13 to engage the roller 11 in its peripheral groove 13'; as said cam further rotates, it raises the roller 11 of the arm 9 which causes the lay-beam 2 with the reed 1 to rock on the supporting shaft 5 in opposite direction until it returns to its vertical open position (FIG. 1), thereby completing the normal operating cycle.

FIG. 4 shows, by way of example, an arrangement with change of cams if it is desired to change the strokes of the lay beam. In this case, a cam 21 of different periphery is associated with cam 12, and a cam 22 is added to cam 13, which cam 22 has also a circumference different from that of cam 13. Said cams form a block or unit rotating with shaft 14 and can be axially displaced by a key 23 so to bring cams 21 and 22 in contact with the rollers 10 and 11. Said cams will be axially displaced during rotation when said rollers are on a sector of conforming periphery in order to avoid sudden sharp change from the one to the other position. The axial displacement may be carried out, e.g. by means of a fork 24 whose prongs 25 engage a groove 26 of the cam block. The fork receives a pivotal movement on pin 27 by means of arm 28 which may be actuated from a suitable element of the loom.

I claim:

1. In a beating up mechanism for weaving machines which comprises a lay pivotally supported at its two ends, a reed carried lengthwise by said lay, at least two rotating cams mounted on a common cam shaft, a pair of divergent arms secured to said lay, each arm carrying at its end a roller riding on one of said cams, said cams being arranged to impart to said lay and reed a reciprocating movement, a drive shaft driving said cam shaft and a flywheel on said drive shaft, said two rotating cams comprising a first cam having a projection producing forward movement of the lay and reed into beating up position, and a second cam having a depression angularly displaced with respect to the position of the projection in said first cam receiving the cooperating roller when the other roller is in contact with said projection, said second cam having a projection following said depression

so as to cause the backward movement of lay and reed into picking position,

the improvement wherein a cam of different periphery is added to said first cam, forming therewith a first cam set, and a cam of different periphery is added to said second cam, forming therewith a second cam set, said two cam sets forming an axially displaceable unit rotating with said cam shaft for selective engagement of said first and second cams, or of said cams of different periphery with said rollers, thereby altering the operation of said lay and reed.
